* cited by examiner

Primary Examiner — Philip S Hyder*Assistant Examiner* — Keith Frank(74) *Attorney, Agent, or Firm* — Alix, Yale & Ristas, LLP(57) **CLAIM**

The ornamental design for the bottle, as shown and described.

DESCRIPTION

FIG. 1 is a perspective view of a bottle showing our new design;

FIG. 2 is a front view thereof, the rear view being identical;

FIG. 3 is a top plan view thereof;

FIG. 4 is a bottom plan view thereof;

FIG. 5 is a left side elevation view thereof; and,

FIG. 6 is a right side elevation view thereof.

The broken line portion of the figure drawings is included to show portions of the bottle that form no part of the claimed design.
